LOOP CUTTER FOR MULTIPLE SHUTTLE LOOMS

Henry E. Littlejohn, Greenville, S. C., assignor to
 J. P. Stevens & Co. Inc., Greenville, S. C., a
 corporation of Delaware

Application October 6, 1950, Serial No. 188,713

4 Claims. (Cl. 139—266)

1

This invention is concerned with the provision of means for cutting selvage loops formed during the weaving of cloth on looms having shifting shuttle boxes in which one or more shuttles is out of action for an appreciable number of picks.

In the weaving of cross bar fabrics utilizing multiple shuttle looms, in which the boxes holding the inactive shuttles are shifted vertically to positions above or below the lay, a loop of filling is formed along the selvage extending from the last pick of the bar formed by the filling of one shuttle to the first pick at the beginning of the next bar formed by the filling of the same shuttle. These selvage loops if of noticeable length must be removed to make the fabric salable. It is difficult, if not impossible, to remove them by singeing, and it is laborious and expensive to remove them by hand.

The present invention provides means acting automatically during the weaving operation by which such long loops are cut or severed so that the resulting free ends may thereafter be more readily cut off close to the selvage.

The present invention is designed to function whether the out-of-action shuttle has been dropped below the lay or raised above the lay during its period of inaction. The device of the invention has no moving parts and will function for an indefinite period without attention.

The invention will be more particularly described with the aid of the accompanying drawings in which:

Fig. 1 is a plan view of a fragmentary section of warp and cloth during the weaving process showing a portion of the breast beam and a temple to which the loop cutter is affixed.

Fig. 2 is a side elevation looking from the right of Fig. 1, showing in addition the lay, reed and shuttle boxes.

Fig. 3 shows the position of the filling of the inactive shuttle after weaving has proceeded a short distance beyond the position shown in Fig. 1 when the inactive shuttle first went out of action.

Fig. 4 is a plan view similar to Fig. 3 with the filling of the inactive shuttle which will subsequently form a long selvage loop, having moved to a position where it is caught by the loop cutter.

Fig. 5 shows the first pick laid by the previously inactive shuttle after the shuttle has gone back into action with the selvage loop caught by the cutter.

Fig. 6 is similar to Fig. 5 after additional picks

have been laid with the loop tightening on the cutter bar just prior to severance.

Fig. 7 is a front elevation showing the loop cutter attached to the face of the temple and its general relation to the cloth.

Fig. 8 is an elevation looking from the left of Fig. 7.

Fig. 9 is a vertical section on the line 9—9 of Fig. 7.

Fig. 10 is a vertical section on the line 10—10 of Fig. 7.

Fig. 11 is a front elevation of the body of the loop cutter with the cutter bar removed, the cutter bar position being indicated in dotted lines.

Fig. 12 is a plan view of the cutter bar removed from the body.

Referring to Fig. 1 there is shown a plan view of a portion of a loom with a fragmentary section of the cloth as it is being woven. The breast beam 2 supports in the usual manner a temple standard 4 having the usual shank 6 and temple 8. These parts are conventional and constitute no part of the invention in themselves. The selvage loop cutter however which comprises the invention is attached to and cooperates with the temple to cut the selvage loops that are successively formed.

The woven cloth 10 which is moving through the loom in the direction of the arrow has had its last pick laid at the position 12 to which point it has been beaten up by the reed. The warp is indicated at 14. Further details of the construction of Fig. 1 are shown in Fig. 2 in which it can be seen that the temple 8 is of conventional construction with the cloth arranged to run over the two gripping rollers 16 and 18 which hold the cloth at full width for a limited distance beyond the weaving point. In Fig. 2 is shown additionally the lay 20, the reed 22, and the shuttles and shuttle

boxes are indicated at 24, 26 and 28. The active shuttle is at 26 while the inactive shuttles are at 24 and 28.

Let us assume that the shuttle that is now in box 24 laid its last pick at 12, as viewed in Fig. 1.

45 This pick has been beaten up and shuttle 26 is now in action, weaving the cloth above the pick 12. That part of pick 12 that extends from the selvage to the inactive shuttle in box 24 is indicated in Fig. 1 at 30, which position the yarn will

50 assume when the lay is forward, and at 30' which indicates the position the yarn will assume when the lay is at its rear position. As the shuttle boxes move forward and backward with the lay, the yarn of the inactive shuttle will swing forward and backward between positions 30 and 30'.

in a loose drooping fashion. This condition of the yarn of the inactive shuttle will prevail whether the shuttle box has dropped to the position at 24, or has risen to the position at 28.

If there are two or more inactive shuttles the threads leading to them from the selvage will all behave in like manner, and each will in due course be caught and cut as explained herein-after.

As weaving progresses the active shuttle produces the series of picks indicated at 32 in Fig. 3 and the pick 12 now in the cloth moves toward the temple 8. In so doing, the inactive filling indicated at 30 and 30' is carried along toward and through the temple and in due course comes into contact with the loop cutter indicated generally in the drawings at 34 and which is attached to the vertical face of the temple.

The loop cutter, which will now be described, has its effective edges in the form of a V which straddles the selvage, with the main portion of the body above and partly over the cloth and with an extension carrying the cutter bar or element extending a short distance under the cloth. It will be understood that the loop cutter is located on the temple that is at the side of the loom containing the vertically movable shuttle boxes and it is at that side of the cloth that the selvage loops that must be cut are formed.

The loop cutter comprises a body member 36 having at its lower portion a laterally extending extension 38 which extension carries a cutting element 40. The configuration of the upper portion of the body member 36 is of no particular significance other than that it should be shaped for application to the temple. However, the downwardly facing thread directing edge 42 which overhangs the edge of the cloth is of importance as it is this edge which directs the inactive filling to a position where it will be subsequently caught and severed by the cutting element 40. The body member 36 is affixed to the face of the temple by screws 44 passing through slots 46 which provide for vertical adjustment.

It will be noticed that the thread directing edge 42 terminates at an apex 48 at which point it meets with reversely turned edge 50 constituting part of the top edge of the extension 38. The outer end of extension 38 has affixed to its raised upper surface the cutting element 40 by means of suitable screws 52. The nature of the cutting element itself can be seen in the succession of views in Figs. 8, 9, 10 and 12. The left hand end as viewed in Fig. 8 is of sufficient size to be readily anchored to the top of extension 38. In Fig. 9, taken on the section 9-9 of Fig. 7, it can be seen that the cutting element has its right side formed to present a cutting edge 54 and is at this position spaced upwardly from the reversely turned edge 50 whereby a thread may pass freely therebetween. The free end of the cutting element indicated at 56 narrows down and is spaced from the thread directing edge 42 at the point where the two parts pass by a relatively small distance. This distance is however sufficient to permit a filling thread such as 30, 30' to pass between the parts but once the thread has passed below the end 56 of the cutting element there is little likelihood of its escaping from this position. The cutting element per se removed from the extension 38 is shown in plan in Fig. 12.

With the construction of the loop cutter now in mind, the sequence of events disclosed in Figs. 3 to 6 may be better understood. As the pick 12, being the last pick of the inactive shuttle,

advances with the woven cloth, the free end thereof, being indicated at 30 and 30', will pass beneath the thread directing edge 42 of the body member 36. As the advance of pick 12 continues, the thread 30 will engage edge 42 and be drawn downwardly along the edge to the apex 48. In reaching this point it will of necessity pass through the narrow opening or space 57, see Fig. 10, between the said thread directing edge 42 and the free end 56 of the cutting element 40 to be caught thereunder, as indicated in Fig. 4. There after, as the lay moves back and forth carrying the inactive shuttle with it and causing thread 30 to swing from its forward position to its rearward position at 30', such movement will not induce the thread to escape from its trapped position at the apex 48 under the free end 56 of the cutting element. This trapped condition will prevail regardless of the position of the inactive shuttle.

In due course, the cloth advances to the position of Fig. 5 and in accord with the pattern the inactive shuttle now comes back into operation and lays its first pick 58. In so doing, it leaves behind it a selvage loop 60, the forward end of which extends from pick 12 along the selvage over the reversely turned edge 50 of extension 38 and under the end 56 of cutting element 40. At this point the loop 60 will be under that part of the cutting element 44 at which is located the cutting edge 54. In this way, the loop formed when the inactive shuttle goes back into action, is positively caught under cutting element 40.

Weaving then continues as indicated in Fig. 6 so that pick 58 has advanced to a position beyond cutting element 40 and in so doing the loop is tightened against cutting edge 54. Thereafter as soon as the cloth has advanced a sufficient additional distance, the tension on the loop as applied by cutting edge 54 will be sufficient to sever the loop into two portions, one being a relatively short portion which is the end extending from pick 58, and the other being a relatively long portion which is the end extending from pick 12.

The loop cutter of the present invention will function to cut any loop formed in connection with an advance of the cloth sufficient to cause the thread from the inactive shuttle to be drawn down along the thread directing edge 42 to pass by and under the free end 56 of the cutting element.

From the foregoing description it will be seen that there is positive means in the form of the thread directing edge which causes the thread of the inactive shuttle to move to a position at the apex 48 as soon as the cloth has advanced through the temple an adequate distance. In arriving at the said apex, the thread must pass through the narrow opening 57 separating the face of the body member from the free end 56 of the cutting element. Thereafter, due to the nature of the movement of the thread 30 as the lay moves back and forth, I have found that the thread will not escape from its trapped position under the cutting element. Accordingly, the cutting element is able to function any time thereafter to cut the loop subsequently formed when the inactive shuttle goes back in operation.

It is my intention to cover all changes and modifications of the example of the invention herein chosen for purposes of the disclosure which do not constitute departures from the spirit and scope of the invention.

I claim:

1. A selvage loop cutter designed to be affixed to the front of a temple comprising a body member in the form of a vertical plate having a downwardly facing thread directing edge sloping downwardly and outwardly and terminating in a reversely turned edge, which edges at their junction together form an apex, a cutting element fixed with respect to said body with a free portion extending substantially horizontally outwardly to a point beyond said apex and crossing said thread directing edge and spaced closely therefrom, the distance between said element and thread directing edge being at a minimum at a position near the lower limit of said directing edge, said cutting element being spaced from said reversely turned edge, whereby the thread of a shuttle out of action may be guided downwardly along said directing edge to reach said apex and in so doing pass below the end of said cutting element.

2. A selvage loop cutter comprising a unit including a body member and an extension therefrom together forming a V-shaped opening in said unit, the said opening when said unit is fixed to the front of a temple being adapted to straddle the selvage of cloth in a loom close to the point of weaving, said body member having a downwardly facing and sloping edge forming one side of said V, a cutter bar attached to the said extension at a position remote from the apex of said V-shaped opening and having its free end extending in a direction to cross the said downwardly facing edge of said body member in close proximity thereto, said cutter bar being spaced from said extension whereby a thread having passed between said sloping edge and cutter bar may thereafter move to a position between said cutter bar and extension and away from said apex.

3. A selvage loop cutter designed to be affixed to the front of a temple comprising a vertical plate body member having a downwardly outwardly sloping under edge, an extension extending inwardly from the lower outer part of said

body, the upper edge of said extension meeting said under edge to form an apex, a cutting element attached to said extension having a free portion extending horizontally outwardly and crossing said lower edge in close proximity thereto and spaced from said upper edge of said extension, the end of said cutting element terminating above and beyond said apex.

4. In combination, in a loom of the type having a plurality of shuttle boxes on one side of said loom, a temple, a selvage loop cutter mounted on the face of said temple, said loop cutter comprising a body having a downwardly facing thread directing edge sloping downwardly and outwardly and crossing over the selvage of the cloth being woven in said loom and terminating in a thread controlling apex below said cloth, an extension of said body extending laterally inwardly below said cloth, a cutting element attached to said extension below said cloth and having a free portion extending horizontally outwardly beyond said cloth to cross in front of said thread directing edge in close proximity thereto, the end of said element being above and beyond said apex, whereby the thread from an out-of-action shuttle will be directed to said apex to pass by and to a position under said cutting element as said cloth advances through said temple and whereby upon said out-of-action shuttle coming back into action, said thread will form a selvage loop passing under said cutting element, said cutting element acting upon a sufficient further advance of said cloth to sever said loop.

35 HENRY E. LITTLEJOHN.
